UNITED STATES PATENT OFFICE.

WILLIAM H. DE LYLE, OF ALBUQUERQUE, NEW MEXICO.

OPERATING DEVICE FOR WINDMILLS.

1,216,087.

Specification of Letters Patent. Patented Feb. 13, 1917.

Application filed March 22, 1915. Serial No. 16,172.

To all whom it may concern:

Be it known that I, WILLIAM H. DE LYLE, a citizen of the United States, residing at Albuquerque, in the county of Bernalillo, 5 State of New Mexico, have invented certain new and useful Improvements in Operating Devices for Windmills; and I do hereby declare the following to be a full, clear, and exact description of the invention, such as 10 will enable others skilled in the art to which it appertains to make and use the same.

This invention relates to a wind-mill.

An object of the invention resides in the provision of a device of this character which 15 may be used to pump water from a well, and one wherein a continuous reciprocation will be imparted to the pump plunger.

A further object of the invention is to so construct the device that, as the plunger 20 ends the movement in one direction and starts the movement in the other direction, there will be no jar incident to the reversal of the direction of movement.

A still further object of the invention re- 25 sides in the provision of mechanism whereby the mill may be rendered inoperative and the rotation of the wind wheel simultaneously arrested.

With these and other objects in view, such 30 as will appear as the description progresses, my invention comprises the combination and arrangement of parts as set forth in and falling within the scope of the appended claims.

35 Referring to the drawing:

Figure 1 is an elevation of a device constructed in accordance with my invention looking at the edge of the wind wheel.

Fig. 2 is a fragmental elevation taken 40 at right angles to Fig. 1, with the wind wheel removed.

Fig. 3 is a similar view looking at the opposite side of the device to that shown in Fig. 2.

45 Fig. 4 is a plan view.

Fig. 5 is a longitudinal sectional view taken on line 5—5 of Fig. 4, showing the mechanism for raising and lowering the pump rod.

50 Fig. 6 is a section on line 6—6 of Fig. 4 taken at right angles to Fig. 5.

Fig. 7 is a fragmental detail of the brake mechanism, showing the brake in its operative position and the tail in such position 55 as to maintain the wind wheel out of the wind.

Fig. 8 is a fragmental detail of the connecting rod and the guide therefor.

Referring to the drawing wherein like parts are indicated by like characters 60 throughout the several views:—

In the embodiment of my invention disclosed I have provided a tower 1 on the upper end of which is a cylindrical bearing member 2. Revolubly mounted within this 65 bearing member 2 and extending upwardly therefrom is a main supporting frame 3 of rectangular formation and having a circular portion 4 adjacent the lower end thereof for engagement in the bearing member 2. 70 This supporting frame 3 extends upwardly from the bearing member 2 and has shafts 5 and 6 rotatably mounted in the bearing members 7. These shafts are in alinement and the inner ends thereof have disks 8 se- 75 cured thereto leaving a space 9 therebetween. These disks are provided with a plurality of peripherally arranged notches 10. Secured to the outer ends of these shafts 5 and 6 are gears 11 and 12, respectively. 80

Rotatably mounted in a horizontal bearing 13 is a shaft 14 on one end of which is a gear 15 meshing with the gear 11 on the shaft 5 and on the other end of which is a gear 16 meshing with the gear 12 on the 85 end of the shaft 6.

Secured to one end of the shaft 14 is a wind wheel 17 of any desired construction. It is obvious that when the wheel 17 is rotated by the wind, motion will be imparted 90 to the shafts 5 and 6 through the afore-mentioned gears to impart rotative movement thereto and to the disks 8.

In order that the pump rod may be recip- 95 rotated by the rotation of the disks 8, I have provided a connecting rod 18 of a thickness slightly less than the width of the space 9 and having a plurality of outwardly extend- 100 ing rollers 19 which are secured to the rod 18 by suitable pins 20, on the ends of which are nuts 20'. These rollers are adapted to engage successively in the notches 10 in the disks 8. The uppermost of these rollers 19 is considerably longer than the remainder and during the movement of the connecting 105 rod engages in the guides 21 on the interior of the frame 3 to prevent displacement of the connecting rod from the disks 8. The lower end of this connecting rod is swivelly connected to the pump rod. 110

In order that the wind wheel 17 may be kept in or out of the wind at the will of the

operator, I have provided a tail 22 which has a loop 23 on one end thereof through which loop an angular member 24 extends, which member is pivotally engaged with the 5 frame 1.

Connected to the tail 22 is a flexible member 25 which extends into the frame 3 and downwardly through the same within the reach of the operator.

10 Mounted on the shaft 14 adjacent the gear 15 is a disk 26 against which the angular portion 27 of the member 24 bears when the tail 22 is swung into position to hold the wheel 17 out of the wind so that the rotation of the wheel is stopped upon the swinging of the tail 22. In order that this tail may be returned to its initial position to hold the wheel 17 into the wind upon the releasing of the controlling member 25, I have 15 20 pivotally mounted a counter weight 28 on the frame 1 and connected the same to the pivot end of the tail 22 by a flexible member 29 which passes through suitable bearings 30.

25 In order that the connecting rod 18 may be caused to follow the disks 8, upon its upward movement, I have provided a roller 31 which is pivoted to the side of the frame 3 and is normally held against the adjacent 30 face of the connecting rod 18 during its upward movement by the springs 32. It will thus be seen that as the rod 18 rises it will be pushed over the disks 8 by the action of the springs 32.

35 In the operation of this device when the wheel 17 imparts rotary motion to the shaft 14, the intermeshing of the gears 11 and 15 and the gears 12 and 16 will cause the shafts 5 and 6 to be rotated at the same speed. The 40 rotation of these shafts will cause the connecting rod to be moved upwardly and downwardly because of the successive engagement of the rollers 19 in the notches 10 of the disks 8. It will be readily observed that 45 the connecting rod will be moved downwardly upon the engagement of the rollers with the notches on one side of the disks and upwardly upon the engagement of the rollers with the notches on the other side of 50 the disks. This connecting rod is guided during its movement by the engagement of the uppermost of the pins 19 in the guides 21.

55 When the tail is swung to such position that the wheel will be out of the wind the angular portion 27 on the member 24 will be caused to bear against the disk 26 and thus simultaneously arrest the movement of the wheel and also raise the counterweight 28

about its pivot. Upon the release of the operating member 25 for the tail, the counterweight 28 will return the tail to its initial position and throw the wheel again into the wind. 60

From the foregoing description it will be seen that I have provided an exceedingly 65 simple and efficient mill by means of which continuous movement will be imparted to a pump rod to cause the same to reciprocate, and I have so constructed the device that as the pump rod starts on its return movement 70 after having completed its movement in one direction there will be no jar incident to the reversal to the direction of movement.

75 While I have illustrated and described a particular embodiment of my invention, I have merely done so for the sake of convenience and I do not wish to be limited to that particular embodiment as it is obvious that numerous changes may be made within the details of construction thereof without in 80 any way departing from the spirit of the invention or exceeding the scope of the appended claims.

What I claim is:—

1. In a wind mill, a frame having tracks 85 thereon, a pair of aligned shafts mounted in said frame and having their ends terminating in spaced relation, notched disks secured to the adjacent ends of said shafts, a reciprocating rod movable between said disks and 90 having pins thereon for engaging the notches in the same, the ends of certain of the pins engaging said tracks to guide the remaining pins into said notches, and spring actuated means for urging the rod toward the centers 95 of the disks during its upward movement.

2. In a wind mill, a frame having tracks, shafts mounted in said frame adjacent each other, notched disks carried by said shafts, a reciprocating element movable between 100 said disks and having track engaging members thereon for engaging the notches in said disks, certain of said members being adapted to engage the tracks on said frame to guide the remaining members into said 105 notches, and means for urging said reciprocating element toward the centers of said disks during certain portions of the reciprocations thereof.

110 In testimony whereof, I affix my signature, in the presence of two witnesses.

WILLIAM H. DE LYLE.
